UNITED STATES PATENT OFFICE.

GEORGE T. PEARSONS, OF NEW YORK, N. Y.

FIRE EXTINGUISHER.

1,417,559.

Specification of Letters Patent. Patented May 30, 1922.

Application filed March 29, 1915. Serial No. 17,878.

To all whom it may concern:

Be it known that I, GEORGE T. PEARSONS, citizen of the United States of America, residing at New York city, county of New York, State of New York, have invented a new and useful Improvement in Fire Extinguishers, of which the following is a specification, reference being had to the accompanying drawing.

10 This invention relates to fire extinguishers in which a fire extinguishing liquid is discharged or expelled from a tank or reservoir by the force of a gas generated in said tank, the gas generating materials being 15 contained in a generator in the tank in a normally separated condition and free from the liquid in the tank.

It is the object of the invention to provide a fire extinguisher of this type which is in 20 the nature of a unit sprinkler apparatus in which means are released by means fusible at a predetermined temperature and above the highest ordinary atmospheric temperature to cause the gas generating materials 25 to admix and generate the gas to expel the fire extinguishing liquid from the reservoir.

In the drawing accompanying and forming a part of this specification Figure 1 is a 30 sectional side elevation of a fire extinguisher illustrating an embodiment of my invention and showing the parts in position with the gas generating materials in a separated condition and free from the liquid in the reservoir.

35 Figure 2 is a similar view but showing the parts in position to permit the admixing of the gas generating materials and the generated gas to enter the reservoir to expel the liquid therefrom; and

40 Figure 3 is a sectional side elevation of a modified form of construction showing the parts in position to maintain the gas generating materials in a separated condition.

Similar characters of reference designate 45 likewise throughout the different views in the drawing.

The embodiment of the invention shown in Figures 1 and 2 consists of a reservoir or tank for a fire extinguishing liquid, such as 50 carbon tetrachloride and having a discharge outlet 14. The liquid is discharged from the reservoir through the medium of gas pressure generated in a receptacle or generator in the reservoir. The gas generating 55 materials are normally maintained in a separated non-reactive condition and free from

the liquid in the reservoir. For this purpose the receptacle is constructed with a pair of sections 2 and 4 to constitute superposed chambers A and B; the lower chamber A of 60 which preferably contains an acid, such as hydrochloric acid, and the upper chamber B a suitable chemical such as bi-carbonate of sodium. The receptacle engages in the top of the reservoir the upper chamber hav- 65

ing screw threaded connection, as at 4^a, with the upper end of the reservoir and serves to close such end. The chamber B has a central outlet in the bottom toward which the inner walls converge, the top being closed by 70 cover 19. The section 2 of the receptacle constituting the chamber A is arranged to have longitudinal movement with respect to section 4 for which purpose section 4 is provided with an annular recess 11 in which the 75 upper end of the section 2 engages to have sliding movement. To shut off the access of the material from the chamber B through the opening in the bottom of chamber 4, I provide a plug 6 which is in the nature of a 80

valve movable with the section 2, but said valve being carried by a stem 5 extending through the section 2 and secured thereto as at 20 and through an opening 15 in the bottom of the reservoir to permit of the actuation thereof from the exterior of the reservoir. The parts are retained in their normal positions with the gas generating materials in a separated condition, as shown in 85

Figure 1, by fusible means, such as a cap 9 90 of fusible material engaging in and sealing the opening 15 through which the stem 5 passes and upon which cap the lower end of the stem rests.

The reservoir and the separated chambers 95 of the receptacle or generator are adapted to be filled one independently of the other. The reservoir is filled with the fire extinguishing liquid through a filler tube 17 passing through the section 4 and having a closure cap 17^b. Chamber A is filled through a tube 16 also passing through the section 4 and having a closure cap 16^a; and the chamber B is filled through a central opening in the cover 19 closed by a screw threaded plug 100 17^a. A cap 22 having screw threaded connection with the reservoir engages over the cover 19 and closures for the respective filler openings, thereby preventing accidental displacement of the closures, and having perforated ears or lugs 27 whereby to suspend the extinguisher. Instead of the lugs 27 the 110

lower end of the reservoir may be externally screw threaded, as at 24, to have screw threaded connection with a plate 25* which may be located in the ceiling or the like, to 5 removably support the extinguisher and as clearly shown in Figures 1 and 2. Engaging in the outlet 14 is a tube or pipe 12 extending up into the reservoir and bent reversely so that the opening to the pipe will 10 lie adjacent the bottom of the reservoir. The other end of the pipe projects through the outlet and is closed by a sprinkler head 13.

The operation of the extinguisher as described operates substantially as follows: Assuming the parts to be in the positions indicated in Figure 1 with the fire extinguishing liquid in the tank and the gas generating materials in the generator in a separated condition maintained in said position by fusible 20 cap 9, the outlet being closed by the sprinkler head 13. As soon as sufficient heat is developed, which will of course be higher than ordinary atmospheric temperature, the cap 9 will be fused or melted releasing stem 5 and 25 permitting it to move downward by its own weight drawing the valve 6 away from its seat in the opening in the bottom of the chamber B permitting the chemical therein to drop into the acid in the chamber A, the admixture of such materials at once generating 30 gas. It will be noted that during the initial movement of the receptacle section 2 and at the beginning of the connection of the chambers A and B, the chamber is not connected 35 to the reservoir, but as the section 2 continues to move down it will be drawn out from the recess 11, as shown in Figure 2, whereby said chamber will be in communication with the reservoir, said movement of the 40 stem and receptacle section 2 continuing until a valve plug 7 carried by the stem engages with a seat 8 in the opening 15 sealing 45 said opening and also serving as a stop to limit the downward movement of the stem with its connected mechanism. To facilitate and assure the receptacle section 2 moving downward when the cap 9 has been fused I provide a spring or springs 10 within said 50 section and tension to force the receptacle section 2 downward. These springs are normally enclosed by tubes 21 fixed in the bottom of the receptacle A to prevent deteriorating action of the acid on the metal of the springs. Section 2 is guided in its movement by adjustable pins 18 fixed in the inner 55 wall of the reservoir with their ends abutting against said section, as clearly shown in Figures 1 and 2.

If desired the valve stem 5 may be utilized 60 to discharge the liquid from the reservoir and the outlet 14 with the sprinkler head 13 secured therein omitted. For this purpose the stem 5 consists of a tube and has a port 25 to connect it to the reservoir and a sprinkler head 26 connected to the end thereof. In

this construction the opening 15 is in the form of a bushing or sleeve screw threaded into the bottom of the reservoir the inner end 8 of which is bevelled, constituting the seat for the valve plug 7 to seal said opening. It 70 will be noted that the port 25 is within the valve 7 and when the valve is seated the liquid will enter said port, pass through the tube and be distributed by the sprinkler head.

In Figure 3 the receptacle or generator is 75 of an integral structure separated into two chambers by the valve 6 and connected to the reservoir by a port or ports 29 in the chamber A. The valve stem is slidably mounted in the bottom of the chamber A passing 80 through a guide 30, the valve being maintained closed the same as in Figures 1 and 2 by the fusible cap 9. When the cap 9 is fused the valve will drop, the dropping of the valve being assured by a weight 28 fixed 85 to the valve stem, when the gas generating materials will admix generating gas which passes through the ports 29 to the reservoir and forcibly expelling the liquid therein through an outlet the same as 14 in Figures 90 1 and 2, in which case the exit of the liquid from the reservoir through the opening therein through which the valve stem 6 passes is sealed by the valve plug 7. If desired the valve stem may be hollow and have 95 the intake port 25 to expel the liquid through the valve stem the same as in Figures 1 and 2.

I claim—

1. A portable sprinkler fire extinguisher comprising in combination a reservoir to 100 contain extinguishing liquid and having a discharge outlet; a gas generator in said reservoir having an outlet leading into the reservoir, said generator having means therein to normally maintain gas generating 105 materials in a separated condition, and said means having a part to extend to the exterior of the reservoir and discharge the liquid from the reservoir therethrough; and fusible means with which said extending 110 portion engages to position said part within the reservoir and with the connected means in the generator in position to maintain the gas generating materials in a separated condition, and the fusing of said fusible means 115 permitting said means to move and the gas generating materials to mix in the generator.

2. In a fire extinguisher, the combination of a reservoir for a fire extinguishing liquid and having a discharge outlet; a receptacle 120 in said reservoir having provisions to normally hold gas generating materials in a separated condition, a part of said receptacle being movable with respect to the other part of the receptacle to permit the materials to admix, substantially as and for the purpose specified.

3. In a fire extinguisher, the combination with a reservoir for fire extinguishing liquid having an outlet; a gas generator in said 130

- reservoir having an outlet leading into the reservoir, a valve to separate said generator into two chambers and normally hold gas generating materials in a separated condition in said generator; a tubular stem connected to said valve passing through and slidale in an opening in the reservoir to the exterior thereof to discharge the liquid from the reservoir; and a fusible closure for the 10 opening through which the stem projects and with which closure the stem engages to normally maintain the stem in position within the reservoir with the valve maintaining the gas generating materials in a separated 15 condition in the generator, the fusing of the closure permitting the movement of the stem with the valve and the mixing of the materials in the generator, substantially as and for the purpose specified.
- 20 4. In a fire extinguisher, the combination of a reservoir for a fire extinguishing liquid and having an outlet; a receptacle in said reservoir for a gas generating material; a second receptacle for a gas generating material longitudinally extensible with relation to the first receptacle and having a part to co-operate with the first receptacle to normally separate the two receptacles and maintain the gas generating materials in a separated 25 condition; a stem connected to said second receptacle extending through an opening in the reservoir; and fusible means co-operating with said stem to maintain the receptacle in position with the materials in the two receptacles separated; the fusing thereof permitting movement of the one receptacle to disconnected the two receptacles to cause the materials to admix and the generated gas to enter the reservoir, substantially as and for the purpose specified.
- 30 5. In a fire extinguisher, the combination of a reservoir for a fire extinguishing liquid and having an outlet; a receptacle in said reservoir having a chamber for a gas generating material and connected to the reservoir; a second chamber for a gas generating material in said receptacle; a valve normally disconnecting said chambers and having a stem to pass through an opening in the reservoir; fusible means co-operating with the valve stem to maintain the valve closed to disconnect the chambers and to close the opening through which the valve stem passes, the fusing thereof permitting the opening 35 of the valve to connect the chambers; and a sprinkler head connected to the reservoir outlet, substantially as and for the purpose specified.
- 40 6. In a fire extinguisher, the combination of a reservoir for a fire extinguishing liquid and having an outlet; means to form a chamber for a gas generating material in said reservoir and connected to the latter; means co-operating with said chamber to form a second chamber in said reservoir for another
- gas generating material, said means constituting the second chamber being longitudinally movable relative to the other chamber and having a stem to pass through an opening in the reservoir; a valve carried by the 45 stem to normally disconnect the chambers; fusible means outside the reservoir to close the opening for the passage of the stem and co-operating with said stem to maintain the valve closed and the second chamber in position to disconnect it from the reservoir, the fusing of said fusible means permitting the opening of the valve to connect the two 50 chambers and the connecting of the second chamber to the reservoir; and a sprinkler head connected to the reservoir outlet, substantially as and for the purpose specified.
7. In a fire extinguisher, the combination of a reservoir for a fire extinguishing liquid; a chamber in said reservoir for a gas generating material; means co-operating with said chamber to constitute a second chamber for a gas generating material; said means having longitudinal movement with respect to the first chamber to connect the second 55 chamber with the reservoir; and a valve carried by said means to shut off one chamber from the other and maintain the gas generating materials in a separated condition.
8. In a fire extinguisher, the combination of a reservoir for a fire extinguishing liquid; a chamber in said reservoir for a gas generating material; means co-operating with said chamber to constitute a second chamber for a gas generating material; said means having longitudinal movement with respect to the first chamber to connect the second chamber with the reservoir; a hollow 60 stem connected to and movable with the means to constitute the second chamber, said stem arranged to pass through an opening in the reservoir and having a port connecting with the reservoir; and fusible means to seal the opening through which the stem passes and co-operating with the stem to maintain 65 the movable chamber in position to cut off communication between said chamber and the reservoir, substantially as and for the purpose specified.
9. In a fire extinguisher, the combination of a reservoir for a fire extinguishing liquid; a chamber in said reservoir for a gas generating material; means co-operating with said chamber to constitute a second chamber for a gas generating material, said means having longitudinal movement with respect to the first chamber to connect the second chamber with the reservoir; a hollow stem connected to and movable with the means constituting the second chamber, said stem arranged to pass through an opening in the reservoir and having a port connecting with the reservoir; a sprinkler head connected to said stem; and a fusible cap to seal the opening through which the hollow stem passes.

and co-operate with the stem to maintain the movable chamber in position to cut off communication between said chamber and the reservoir, the fusing of said cap permitting the valve to open and the admixing of the materials and connecting the movable chamber to the reservoir; and said stem having means to engage in and seal the opening in the reservoir through which the stem passes and to cause the liquid from the reservoir to be expelled through the port in the stem and also limit the movement of the movable chamber.

10. In a fire extinguisher, the combination 15 with a reservoir, of a receptacle for a gas generating material supported in said reservoir; a second receptacle for a gas generating material; a valve normally separating the receptacles and maintaining the gas 20 generating materials in a separated condition in said receptacle; a hollow valve stem extending through an opening in the reservoir and having a lateral port communicating with the interior of the reservoir; and 25 a fusible plug co-operating with said stem to retain the valve in position with the materials in a separated condition in the receptacles, the fusing of said plug permitting movement of said stem and valve to connect 30 the receptacles and the admixing of the materials, substantially as and for the purpose specified.

11. In a fire extinguisher a reservoir for fire extinguishing liquid; normally inert 35 means in the reservoir operable to create and exert pressure on the fire extinguishing liquid to discharge the same from the reservoir; and means normally sealed within the reservoir to discharge the fire extinguishing liquid 40 exteriorly of the reservoir, said inert means being adapted to create pressure and exert the same on the fire extinguishing liquid in the reservoir and the means to discharge the liquid to the exterior of the reservoir being releasable when the temperature 45 adjacent the reservoir reaches a predetermined degree.

12. In a fire extinguisher a reservoir for a fire extinguishing liquid; normally inert 50 pressure creating means within the reservoir operable to create and exert pressure on the fire extinguishing liquid to discharge the same from the reservoir when the temperature adjacent the reservoir reaches a predetermined degree, and means normally 55 within the reservoir adapted to be projected from the reservoir to discharge the fire extinguishing liquid exteriorly of the reservoir.

60 13. In a fire extinguisher a reservoir for a fire extinguishing liquid; means operative to place said liquid under pressure when the temperature adjacent the reservoir reaches a predetermined degree; and means normally 65 within the reservoir adapted to be

projected therefrom to discharge the liquid from the reservoir exteriorly thereof when the liquid is placed under pressure.

14. In a fire extinguisher a reservoir to contain fire extinguishing liquid; means operative to place said liquid under pressure in the reservoir; and means to discharge the liquid exteriorly of the reservoir positioned within the reservoir when the pressure creating means is inactive.

75 15. In a fire extinguisher a reservoir to contain fire extinguishing liquid; means operative to place said liquid under pressure in the reservoir and project a tube from the reservoir through which to discharge the liquid from the reservoir exteriorly thereof; and means releasable at a predetermined temperature to set said pressure creating means in operation.

80 16. In a fire extinguisher, the combination of a reservoir to contain fire extinguishing liquid and having an opening therein; a fusible closure for said opening; a tube through which to discharge the liquid from the reservoir exteriorly thereof positioned within the reservoir by the fusible closure and adapted to be projected through said opening upon the fusing of the said closure; and means set in operation upon the fusing of the fusible closure to place the liquid in 95 the reservoir under pressure.

85 17. In a fire extinguisher, the combination of a reservoir to contain fire extinguishing liquid and having an opening therein; a fusible closure for said opening; means in 100 the reservoir including a tube through which to discharge the liquid from the reservoir exteriorly thereof positioned within the reservoir by the fusible closure to maintain gas generating materials in a separated condition and operative upon the fusing of the 105 fusible closure to project the tube through said opening and cause the gas generating materials to mix to create pressure and place the liquid under pressure in the reservoir. 110

18. In a fire extinguisher, the combination of a reservoir to contain fire extinguishing liquid and having an opening therein; a fusible closure for said opening; a receptacle in the reservoir; means including a tube through which to discharge the liquid from the reservoir and exteriorly thereof maintained in position within the reservoir by the fusible closure to hold gas generating materials in a separated condition in the receptacle and operative upon the fusing of the 120 fusible closure to project the tube through said opening and cause the gas generating materials to mix to generate gas and place the liquid in the reservoir under pressure.

125 19. In a fire extinguisher, the combination of a reservoir to contain fire extinguishing liquid and having an opening therein; a fusible closure for said opening; a recep- 130

5 tacle in the reservoir having an outlet leading into the reservoir; means including a stem to engage the fusible closure to maintain said means in position to hold gas generating materials in a separated condition in the receptacle and operative upon the fusing of the fusible closure to cause the gas generating materials to mix to generate gas and place the liquid in the reservoir under pressure.

10 20. In a fire extinguisher a reservoir to contain fire extinguishing liquid and having an opening; a closure for said opening fusible at a predetermined temperature; a gas generator in said reservoir, said generator having means including a part to engage the fusible closure to position said means and maintain gas generating materials in a separated condition in the generator, and operable upon the fusing of the fusible closure to cause the gas generating materials to mix to generate gas and place the liquid in the reservoir under pressure.

15 25 30 35 40 45 50 55 21. In a fire extinguisher a reservoir to contain fire extinguishing liquid having an opening; a closure for said opening fusible at a predetermined temperature; a gas generator in said reservoir having means to hold gas generating materials in the generator in a separated condition including a tubular member to engage in the opening in the reservoir to discharge the liquid therethrough from the reservoir exteriorly thereof, and normally positioned within the reservoir by the fusible closure and maintaining the gas generating materials in a separated condition in the generator, and operative upon the fusing of the fusible closure to project the tubular member through the reservoir opening and cause the gas generating materials to mix to generate gas and place the liquid in the reservoir under pressure.

22. In a fire extinguisher a reservoir to contain fire extinguishing liquid and having an opening; a closure for said opening fusible at a predetermined temperature; a tube through which to discharge the liquid from the reservoir exteriorly thereof normally maintained within the reservoir by said fusible closure and adapted to be projected through the opening in the reservoir upon the fusing of the fusible closure; and normally inactive pressure creating means caused to be set in operation as the discharge tube is projected through the reservoir opening.

23. In an automatic fire extinguisher, a container for a fire extinguishing fluid,

means adapted automatically to place said fluid under compression when a predetermined temperature is reached and means normally within said container adapted to expel the fluid at a point exterior to said container.

60 65 70 75 80 85 90 95 24. In a fire-extinguisher, the combination of a container for a fire-extinguishing fluid, means adapted to place said fluid under compression, and means adapted to be projected from said container for conveying said fluid to a point exterior to said container and there ejecting it.

25. In a fire extinguisher, the combination of a container for a fire-extinguishing fluid, means adapted to place said liquid under compression, and means for ejecting said liquid at a point exterior to said container, said means being positioned within said container when the compression means is inactive.

26. In a fire-extinguisher, the combination of a container for a fire-extinguishing fluid, means adapted to compress said fluid and to project a nozzle from said container, and means for causing said compression means to become operative.

27. A gas pressure generator for fire extinguishers comprising superposed receptacles to carry gas generating materials, one of which is arranged with an outlet and the superposed receptacle having an opening in the bottom; a closure for said opening to retain the material in said superposed receptacle; and fusible means to retain said closure in closed position for the purpose specified.

28. A gas generator for fire extinguishers comprising superposed receptacles to carry gas generating materials, one of which receptacles is arranged with an outlet and the superposed receptacle having an opening in the bottom; a closure for said opening including a slidably supported stem; and releasable means co-operating with said stem to release the closure and permit the gas generating material in the superposed receptacle to mix with the gas generating material in the lower receptacle for the purpose specified.

29. In testimony whereof, the said GEORGE T. PEARSONS has signed his name to this specification in the presence of two subscribing witnesses, this twenty-fifth day of March, 1915.

GEO. T. PEARSONS.
